UNITED STATES PATENT OFFICE

LOUIS M. JOHNSON, OF CONCORD, CALIFORNIA

TOOTHPICK HOLDER

Application filed March 11, 1930. Serial No. 434,889.

The present invention relates to improvements in toothpick holders and its principal object is to arrange a plurality of toothpicks in the form of a book which allows a person to carry the toothpicks in his pocket and to break them out of the book one after the other as he may need them.

A further object of the invention is to arrange a plurality of toothpicks in book form intended for handing out as advertising matter, the idea being to make the book sufficiently useful to induce a person to keep the same and to read the advertising matter from time to time until the toothpicks are exhausted.

A further object of the invention is to provide a toothpick that is unbreakable, sliverless and sanitary.

A further object of the invention is to provide a toothpick book that may be constructed very cheaply and in which the toothpicks are covered except when the book is opened for the withdrawal of a toothpick, and in which the toothpicks are arranged in spaced relation so that a person may break away one of the toothpicks without touching any of the others.

Further objects and advantages of my invention will appear as the specification proceeds.

The preferred form of my invention is illustrated in the accompanying drawings, in which

Figure 1 shows my toothpick holder or book in perspective view,

Figure 2 shows the holder or book in plan view, the book being opened to disclose the toothpick arrangement; and

Figure 3 is a longitudinal vertical section through the book.

While I have shown only the preferred form of my invention, I wish to have it understood that various changes or modifications may be made within the scope of the claims hereto attached without departing from the spirit of the invention.

In its preferred form my toothpick holder comprises a sheet of material, preferably celluloid, including a base 1 and a plurality of 50 tapered members 2 extending from one edge

thereof, the tapered members projecting in spaced and parallel relation and in the plane of the base. These tapered members are substantially of the length of toothpicks and are intended to be used for that purpose. 55 Where the tapered members or toothpicks join the base, I provide a groove 3 which facilitates the breaking away of the individual toothpicks. The entire device including base and toothpicks is preferably made in the form 60 of a rectangle.

To protect the toothpicks I use a cover 4 of the same width as the base 1 and of a length sufficient that it may be glued to the base with one end as shown at 5, then folded 65 over the points of the toothpicks and fastened to the other face of the base with its other end.

It should be understood that instead of gluing one end of the cover to the base, any 70 other means of fastening may be adopted. For fastening the loose end of the cover to the opposite face of the base 1, I provide a small projection 6 in the base preferably made by bending a small section out of the plane of 75 the base. The free end of the cover is formed with a small slot 7 adapted for engagement with the projection 6. It should be noted that the projection 6 points away from the front edge 8 of the cover and that the recess 80 7 is positioned in such a manner that it can be engaged with the projection 6 only by taking hold of the sheet of celluloid at opposite ends and slightly compressing the same whereby the sheet which is made elastic is 85 bent out of its plane, and the spacing between the projections 6 and the front edge 8 is reduced correspondingly. After the projection 6 has thus been introduced in the slot 7 the grip on the book is released, the sheet 90 of celluloid springs back into straightened position, and the projection 6 takes a firm hold in the slot 7. For opening the cover it is again necessary to subject the device to endwise pressure. 95

The cover itself is principally intended to be used for the display of advertising matter as is indicated on the drawings. One good way of using the device would be for instance 100 by way of cooperation between a garage and

a restaurant, the garage owner carrying the expense of manufacturing or buying the devices and placing thereon his advertising matter, and the restaurant man distributing the devices to his patrons as they leave the restaurant.

It is quite apparent that this method of handing out toothpicks is particularly sanitary since each person comes in contact only 10 with those toothpicks intended for his own use, and the handing out of these toothpick books does away with the promiscuous selection of toothpicks from a large stack or pile practiced at the present time, where each 15 person in selecting one toothpick touches three or four that will be used later by some other person.

The arrangement is very handy, compact and small and adapted for being carried in 20 a vest pocket, the cover serving to keep the toothpicks clean, and the toothpick arrangement being such that each toothpick is firmly held in place until used, and is prevented from working into the cloth material of the 25 suit.

For separating the toothpicks it is merely necessary to open the book, grasp one of the toothpicks near the base, turn it gently whereby the toothpick will break away from 30 the base, and is now ready for use. While I preferably use celluloid for my device, it should be understood that other material will be found practical. For the use of my particular locking means it is necessary that the 35 material be elastic and springy and adapted to yield to endwise pressure.

To facilitate and cheapen the manufacture of my toothpick holders it is advisable to cut two complete sets out of one single sheet of 40 material in one operation. The blank sheet of material would correspond in width to the width of the base, and in length to the combined length of the toothpicks and the double base, so that by a single cutting operation on 45 an intermediate section two sets of toothpicks would be formed, one set adhering to one base and the other set adhering to the other base. The number of toothpicks attached to one base would correspond to that shown in 50 the drawings. In this manner two complementary sets of toothpicks could be formed without waste whatever.

I claim:

1. A toothpick holder comprising a base 55 having a plurality of toothpicks projecting therefrom and made of resilient material, a cover adapted to be folded for enclosing the base and picks, and fastening means for the cover made to release upon applying endwise 60 pressure to the opposite ends of the folded holder and toward the central portion of the latter.

2. A toothpick holder of the character described comprising a base having a plurality 65 of toothpicks projecting therefrom and made

of resilient material, a cover having one end thereof anchored to one face of the base and adapted to be bent back upon itself intermediate of the cover ends so as to enclose the picks, and a projection rising from the base and pointing away from the bend in the cover and arranged for passing through an aperture in the free flap of the cover, whereby the cover can be disengaged from the projection by applying endwise pressure to one of the base ends and the bent section of the cover in a direction toward the central portion of the folded holder.

Signed at Martinez, in the county of Contra Costa and State of California, this 3rd day of March, A. D. 1930.

LOUIS M. JOHNSON.
